TROPHY

Marvin Kramer, Chicago, Ill.

Application January 12, 1959, Serial No. 54,140

Term of patent 7 years

(Cl. D29—23)

Fig. 3.

Fig. 1.

Fig. 2.

Fig. 4.

Fig. 1 is a front elevational view of a trophy embodying my new design;

Fig. 2 is a right side elevational view of the same;

Fig. 3 is a top plan view of the same; and

Fig. 4 is a sectional view thereof taken on the plane of line 4—4 in Fig. 1 and viewed in the direction indicated.

The broken line showing in Fig. 1 is for illustrative purposes only.

I claim:

The ornamental design for a trophy, substantially as shown and described.
